(57) **CLAIM**

The ornamental design for a slim mobile hydraulic fluid cooling assembly, as shown and described.

DESCRIPTION

FIG. 1 is an elevated front and left sided perspective view of the slim mobile hydraulic fluid cooling assembly.

FIG. 2 is an elevated front and right sided perspective view thereof.

FIG. 3 is a bottom front and right sided perspective view thereof.

FIG. 4 is a bottom front and left sided perspective view thereof.

FIG. 5 is a front view thereof.

FIG. 6 is a rear view thereof.

FIG. 7 is a right side view thereof.

FIG. 8 is a left side view thereof.

FIG. 9 is a top view thereof; and,

FIG. 10 is a bottom view thereof.

The broken lines are included as boundary lines and form no part of the claimed design.
